SUNGLASS FRAME FRONT

William G. Wood, Douglassville, Pa., assignor to The Electric Storage Battery Company, Philadelphia, Pa.

Filed May 16, 1963, Ser. No. 74,908

Term of patent 14 years

(Cl. D57—1)

Fig. 1.

Fig. 2.

FIG. 1 is a front view of a sunglasses frame front showing my new design; and,

FIG. 2 is a side view thereof taken from the left of FIG. 1, wherein the fragmentary dot-dash line representation of a temple is for illustrative purposes only.

The rear is plain and flat as indicated in FIG. 2.

I claim:

The ornamental design for a sunglasses frame front, substantially as shown and described.
